Primary Examiner — Dana L Meyrow(74) *Attorney, Agent, or Firm* — Knobbe Martens Olson & Bear LLP(57) **CLAIM**

The ornamental design for a bottle, as shown and described.

DESCRIPTION

This patent or application file contains at least one drawing executed in color. Copies of this patent or patent application publication with color drawings will be provided by the Office upon request and payment of the necessary fee.
FIG. 1 is a front elevational view of a bottle showing my new design.

FIG. 2 is left side elevational view thereof.

FIG. 3 is a rear elevational view thereof.

FIG. 4 is a right side elevational view thereof.

FIG. 5 is a top plan view thereof; and,

FIG. 6 is a bottom plan view thereof.

The evenly-dashed broken lines in the drawings illustrate portions of the bottle that form no part of the claim. The dot-dot-dash broken lines in the drawings define the bounds of the claim and form no part thereof.
